CLAIM

The ornamental design for a baby food feeder, as shown and described.

DESCRIPTION

FIG. 1 is a top, front and left side perspective view of a baby food feeder showing my new design;
FIG. 2 is a top plan view thereof;
FIG. 3 is a rear elevational view thereof.
FIG. 4 is a left side elevational view thereof;
FIG. 5 is a front elevational view thereof;
FIG. 6 is a right side elevational view thereof;
FIG. 7 is a bottom plan view thereof; and,
FIG. 8 is a bottom, rear and right side perspective view thereof.

The broken lines shown in the drawings depict portions of the baby food feeder that form no part of the claimed design.

1 Claim, 4 Drawing Sheets
